UNITED STATES PATENT OFFICE.

MOSES HAMBURGER, OF NEW YORK, N. Y.

DESIGN FOR A PORTIÈRE.

No. 37,784.

Specification for Design.

Patented Jan. 9, 1906.

Application filed December 4, 1905. Serial No. 290,318. Term of patent 7 years.

To all whom it may concern:

Be it known that I, MOSES HAMBURGER, a citizen of the United States, residing at New York city, State of New York, have invented a new, original, and ornamental Design for Portières, of which the following is a specification.

The figure is an elevational view of a portière.

I claim—

The ornamental design for a portière as shown.

MOSES HAMBURGER.
